THEFTPROOF LICENSE TAG

Adolph Lyle, Wanette, Okla.

Application October 30, 1939, Serial No. 302,029

4 Claims. (Cl. 40—125)

This invention relates to a theftproof tag for automobiles.

An object of the invention is the provision of a device for securely locking a tag in place on a holder whereby it is impossible to remove the tag without destroying the holder.

Another object of the invention is the provision of a holder for automobile license tags, one end of the holder being formed with a channel through which the upper end of the tag having a bead is adapted to be forced, the tag adjacent the bead being provided with openings to receive a metal block having resilient wings at the inner ends thereof with the wings being flared outwardly so that when the blocks are placed within the openings at the upper end of the tag, the wings will extend outwardly upon opposite sides of the tag so that when the tag is forced longitudinally of the channel, the wings will be compressed until they reach shoulders formed on the inner opposite walls of the channel when said wings will expand and engage the shoulders and prevent sliding movement of the tag in the holder.

A further object of the invention is the provision of a holder for automobile license tags on which a channel is formed to receive the upper end of the tag with cooperating means on the tag and inner walls of the channel to prevent the tag from being moved longitudinally along the holder after the cooperating means are interlocked in engagement.

This invention will be best understood from a consideration of the following detailed description, in view of the accompanying drawing forming a part of the specification; nevertheless, it is to be understood that the invention is not confined to the disclosure, being susceptible to such changes and modifications as define no material departure from the salient features of the invention as expressed in the appended claims.

In the drawing:

Figure 1 is a view in elevation of a holder supporting a tag and constructed in accordance with the principles of my invention.

Figure 2 is a horizontal section taken along the line 2—2 of Fig. 1.

Figure 3 is a transverse vertical section taken along the line 3—3 of Fig. 1.

Figure 4 is a fragmentary vertical section taken along the line 4—4 of Fig. 2, and

Figure 5 is a fragmentary view in perspective of the tag carrying a locking means.

Referring more particularly to the drawing, 10 designates a holder which is formed of metal such

as iron or steel which will resist ordinary means for removing it from the automobile.

The holder at its lower end is provided with a depending lip 11 which provides sufficient surface for securing the holder to the automobile. 5 Directly opposite the lip 11 is formed a substantially V-shaped slot 12 to provide a left handed section 13 and a right handed section 14. On the upper edge of the holder of each section is formed a housing 15 which is made of metal 10 and which is of sufficient strength or hardness to prevent some unauthorized person from cutting through the channel.

Each housing is provided with a vertical channel, generally designated by the numeral 16, and 15 a horizontal channel 17. The ends 18 and 19 of the horizontal channel 17 are located upon opposite sides of the vertical channel 16. It will be noted that these ends are enclosed within the housing. The vertical channel, however, as 20 shown at 20 opens at its lower end through the bottom 21 of the housing, in order to receive the upper edge of an automobile license tag, generally designated by the numeral 22.

The side edges of the holder, as shown at 25, 25 are cut away to provide ears 26. These ears are provided with slots 27 which receive bolts passing through perforations 28 formed in the tag 22 for maintaining the lower end of the tag tight against the holder 10 to prevent vibration of 30 the tag when the vehicle is being operated.

The tag adjacent but inwardly of the periphery is provided with a bead 30. The upper longitudinal portion 31 of the bead is provided with a pair of openings 32 and 33. A block 34 is located within the opening 32 while a block 35 is located in the opening 33. Each of these blocks is formed of metal. The block 34 is provided with wings 36 adapted to engage shoulders 37 formed in the inner side walls of the housing 15. These shoulders are in such a position that when the wings 36 are moved inwardly with the tag 22 that they will fall into the pockets 38 with the free ends of the wings engaging the shoulders.

The block 35 is also provided with a pair of wings 40 which drop into pockets 41 so that the free ends of the wings will engage shoulders 42 located at the ends of the pockets. It will be noted that the wings 36 and the wings 40 when 50 the tag is in locked position project towards each other or towards the center of the tag.

When it is desired to place a tag within the holder the upper end of the tag is neatly inserted within the vertical slot 20 at the left hand 55

side of the holder 10. The tag is then forced inwardly with the bead 30 riding within the space formed by the vertical and horizontal grooves 16 and 17, respectively. When the opening 33 reaches the space between the inner edges 12 of the sections 13 and 14 the block 35 is inserted within the opening 33 with the wings 40 pointing towards the left and located upon the opposite sides of the tag 22.

10 The block 34 is then placed within the opening 32 with the wings 36 pointing towards the right and then the tag is forced towards the right until the free ends of the wings 36 reach the left hand end of the housing 15. The wings are 15 then pressed together so that they will enter the horizontal slot 17 and the tag is then further forced to the right until the ends of the wings 36 engage the shoulders 37 and the ends of the wings 40 slip over the shoulders 42 and are nested 20 in the pockets 41.

In this position of the tag it will be impossible to move the tag either to the right or left because if the tag is moved to the left the shoulders 42 in cooperation with the free ends of the wings 25 40 will prevent such movement while when it is attempted to move the tag to the right the shoulders 37 being engaged by the free ends of the wings 36 will prevent such movement.

It will be appreciated that since the wings 36 30 and 40 are spring fingers and since they are flared outwardly from the tag 22 to a distance greater than the width of the channel 17 the free ends of the wings will snap into their various pockets automatically when the tag has been shoved into 35 position.

The only way to remove the tag after it has thus been locked in position would be to destroy the plate holder 10.

The blocks because of their position in the 40 horizontal chamber 17 prevent the tag from being pulled downwardly from the housings while the fingers and shoulders prevent lateral displacement.

While I have shown two housings 15 on the 45 plate 10, with a V-shaped space between the sections 13 and 14 for the convenience of inserting the block 35 within the opening 33, it will be appreciated that a single housing may be provided to receive the upper end of the tag. In that 50 event, the block 35 is inserted in the opening 33 with the fingers pointing towards the left and the tag with the positioned block is moved to the right until the opening 34 approaches the left end of the housing when the other block is inserted as described above and the tag is then 55 forced into locked position.

I claim:

1. In combination with a tag provided with

spaced openings, a holder comprising a metal plate, a housing rigidly formed on the upper end of the plate and provided with a horizontal channel extending the length of the housing to receive the upper edge of said tag, a block located in each 5 opening, flared wings projecting inwardly from the blocks and located upon each side of the tag, the inner walls of the housing having pairs of oppositely disposed shoulders adapted to be engaged by the free ends of the wings when the 10 full length of the upper edge of the tag has been forced longitudinally through the channel for immovably securing the tag to the plate.

2. In combination with a tag provided with spaced openings, a holder comprising a metal 15 plate having a pair of spaced outwardly extending sections, a housing rigidly secured to the free end of each section, the inner ends of the housings being spaced from each other, said housings being provided with aligned channels to 20 receive an edge of the tag and to completely enclose the openings, a block located in each opening, the walls of the channels having shoulders, wings on the blocks, projecting towards the inner ends of the channels and adapted to engage 25 the shoulders to prevent removal of the tag from the housings.

3. In combination with a tag provided with spaced openings, a holder comprising a metal 30 plate having a pair of spaced outwardly extending sections, a housing rigidly secured to the free end of each section, the inner ends of the housings being spaced from each other, said housings being provided with aligned channels to receive an edge of the tag and to completely enclose the 35 openings, a block located in each opening, the walls of the channels having shoulders, flared resilient wings on the blocks, projecting towards the inner ends of the channels and adapted to engage the shoulders to prevent removal of the 40 tag from the housings, said wings adapted to be compressed towards each other when the edge of the tag is forced through the channels in the housings.

4. In combination with a tag provided with 45 spaced openings, a holder comprising a metal plate having a pair of spaced outwardly extending sections, a housing rigidly secured to the free end of each section, the inner ends of the housings being spaced from each other, said housings being 50 provided with aligned channels to receive an edge of the tag and to completely enclose the openings, a loosely mounted block located in each opening, cooperating means on the blocks and on the walls of the channels for preventing 55 removal of the tag from the housings.

ADOLPH LYLE.
